UNITED STATES PATENT OFFICE.

HENRY P. SCHOENKY, OF ST. LOUIS, MISSOURI, ASSIGNOR TO AMERICAN SHOE MACHINERY & TOOL COMPANY, OF ST. LOUIS, MISSOURI, A CORPORATION OF MISSOURI.

PRESSER-FOOT FOR SEWING-MACHINES.

1,242,608.

Specification of Letters Patent.

Patented Oct. 9, 1917.

Application filed November 27, 1916. Serial No. 133,594.

To all whom it may concern:

Be it known that I, HENRY P. SCHOENKY, a citizen of the United States, and a resident of the city of St. Louis and State of Missouri, have invented a new and useful Improvement in Presser-Feet for Sewing-Machines, of which the following is a specification.

This invention relates particularly to machines for sewing outsoles on shoes, but is adapted for all classes of work which may vary considerably in thickness.

The objects of the invention are simplicity of construction, strength, durability, accessibility, and capacity for operating upon all classes of work without resetting or adjustment. Further objects of the invention appear hereinafter.

The invention consists in a presser foot having on operating bar slidably engaging its shank, which clamps it down and raises it automatically during the stitch forming operation, and which is self-adjusting to accommodate different thicknesses of work.

The invention further consists in the arrangement of the parts for convenient operation of the machine, and for easy inspection and adjustment or repair, as hereinafter described. What the invention consists in is further set forth in the appended claims.

A machine embodying the invention in an operative form is shown in the accompanying drawings forming part of this specification. The same reference characters are used throughout the several views of the drawings to designate the same parts of the machine.

Referring to the drawings,

Fig. 1 is a front elevation of a machine embodying the invention, part of the head being broken away to disclose the presser foot operating clamp bar and spring;

Fig. 2 is a part cross-section on the line 2—2 in Fig. 1, and part side view of the right side of the machine;

Fig. 3 is a cross-section on the line 3—3 in Fig. 2, looking toward the front of the head; and

Fig. 4 is a horizontal cross-section of the head on the line 4—4 in Fig. 3.

The machine shown in the drawings has a main frame consisting of a base 10, side

walls 11 and a front wall 12. Projecting forward from the front wall is a table 13 for supporting the work being sewed, and two arms 14 for supporting the presser foot 33 and needle bar 43. The front ends of the arms 14 support a plate 15 which is provided with a chamber for heating it by steam, which is circulated through the steam chamber by means of pipes 18. This arrangement keeps the needle bar, presser foot, and front plate warm and prevents the wax on the thread from getting hard.

The work table has a slot through it parallel to its front edge for the awl and needle to work through. The work is held by the operator with its top side up, and is guided by hand. The work is fed forward for each stitch by the awl 20, which operates from below the work table in front of the shuttle 52. The awl is carried by a vertically and sidewise movable holder 21, which also carries a channel cutter 22 for grooving the underside of the work to form a channel for the thread. The work is held in place on the table by a presser foot 32 which operates from above the table.

There are two threads used in forming the stitch, the top thread 40 being led through the eye of the needle 41 which operates from above the work, and the bottom thread being supplied from a bobbin which is carried by the shuttle 52 which operates below the work table. The stitch forming mechanism comprises also a looper 60, which operates below the table in connection with the shuttle, and a take-up lever 70 which co-operates with the needle for measuring the length of top thread required for each stitch, and for pulling both threads tight at the completion of the stitch. The top thread is locked by a thread clamp, which is released during the thread measuring movement of the take-up lever. The needle and awl are both straight, but the invention is not restricted to a straight needle and a straight awl.

The awl, feeding mechanism, presser foot, needle, shuttle, looper, take-up device and thread lock are all operated from a rotating cam disk 80 mounted on the main shaft 81 of the machine. The main shaft 81 is horizontally journaled in bearings in the side walls 11 of the machine frame, and has a

hand wheel 83 on its right hand end. The main shaft is driven from a suitable source of power, such as a foot pedal and crank or a small electric motor, by means of a belt 5 running in the groove 84 in the hand wheel.

A wax pot 66 is provided for waxing the thread. The wax pot is located on top of the frame of the machine at the back, and is steam jacketed for keeping it hot. The 10 thread is led to the wax pot from any suitable source of supply, such as a spool, not shown in the drawings.

The awl holder 21 is mounted to slide horizontally from side to side in a slide box 23, which in turn is slidably arranged 15 for movement up and down. The awl holder is moved back and forth by means of suitable adjustable connections from the lever 27 which is oscillated periodically by the cam 80. The slide box is moved up and down by means of a bell crank lever 29 to which it is connected by a link 30, the rear end of the bell crank lever carrying a roller which co-operates with a groove 31 in the 20 face of the cam 80. The shape of the cam groove 31 is such that the awl is raised to penetrate the work, is held up until the feeding device has moved the awl into vertical alinement with the needle, and is withdrawn in advance of the downward movement of the needle.

Presser foot mechanism.

The presser foot 32 is mounted on the 35 lower end of a square slide bar 33 which is guided for up and down movement in suitable slots in the front of the arms 14 behind the steam chamber plate 15. The toe of the presser foot rests upon the work over 40 the work table, and is provided with a slot 34 through it in vertical alinement with the slot in the work table. The presser foot is held down by a clamp lever 35 which co-operates with a cam operated rocker arm or 45 lever 36. The clamp lever has a square hole in it near its front end through which the square slide bar 33 passes loosely. The clamp lever is supported at its front end by means of a spring 331 which is mounted 50 on a rod 332 which projects up from the bottom of a pocket on the inner side of the front plate 15 between the arms 14 of the machine. The rod 332 passes loosely through a hole in the front end of the clamp 55 lever, and carries a stop 333 above the end of the clamp lever. The rod 332 may be adjusted vertically by means of a set screw 335 to position the clamp lever and control the tension in the spring 331. A spring 60 334 bears upon the top of the lever clamp 35. Collars 336 are arranged between the springs and the clamp lever. The rod 332 is enlarged where it goes through the clamp lever to hold the collars against the springs. 65 The lever is positioned by the springs 331

and 334 to hold it horizontal and free of the slide bar when the clamping lever is not held down at its back end by the rocker arm or lever 36, to which it is connected by the link 361.

The rocker lever 36 is pivoted at its middle upon a transverse shaft 73 to oscillate in a vertical plane behind the presser foot slide bar. The back end of the rocker lever has a roller 362 which rolls on one edge of 70 the periphery of the cam disk 80 to hold it up and thereby clamp the presser foot down. A spring 363 holds the roller in contact with the cam. The presser foot is free to lift vertically through the hole in the clamp 80 lever when the latter is horizontal, and at such times the work may be fed by the awl and positioned or guided by the operator. The presser foot is automatically released during the period of feeding the work by 85 the awl by a suitable notch 37 in the edge of the cam disk; and a second short notch 38 permits the release of the clamp at the end of the stitch for the purpose of shifting the work if desired. The notch 37 has 90 a deep portion 371 into which the rocker lever drops and raises the presser foot during the feeding of the work by the awl. The springs 331 and 334 permit either the raising or the clamping down of the presser 95 foot by the movement of the clamp lever after it has tilted enough for it to clamp the presser foot bar.

A hand lever 39 for lifting the presser foot by hand is pivoted to the post 151 on 100 the front plate 15 of the arm 14. The hand lever has an arm 390 which is provided with a cam slot 391 in which a pin 392 on the slide bar works. A light spring 393 holds the hand lever and presser foot down. The 105 hand lever can be operated conveniently only when the roller 362 is in one of the cam notches 37 or 38, although the front end of the clamp lever may be depressed by means of a suitable tool to release the slide 110 bar regardless of the position of the cam.

Operation of the presser foot.

By turning the hand wheel 83 so as to bring the cam notch 38 under the roller 115 362 on the lever 36 which operates the presser foot clamp, the presser foot is released and the work can be brought in position on the work table under the presser foot. A slight movement of the top of the 120 hand wheel away from the operator clamps the presser foot down on the work and the machine is ready for operation by power. The cam is rotated in the direction of the arrow in Fig. 2, and the shapes of the various cam grooves and shapes and arrangement of the levers and links are such as to produce synchronous movement of the operating parts as follows:

First, the awl moves up through the work, 130

moves sidewise toward the left to feed the work under the needle, and then withdraws down through the work and moves back toward the right to its initial position out of the way of the needle. During the side-
5 wise movement of the awl to feed the work the presser foot is released. At all other times the presser foot is clamped down until the stitch is completed, when it is momentarily released to permit removing the work
10 from the table. The awl operating mechanism and thread forming mechanism may be similar to those shown in my application, Serial No. 71,179, filed Jan. 10, 1916, and reference is made to said application for a
15 complete description of suitable mechanisms for operating the awl, needle bar, shuttle, looper, thread measuring device and thread lock.

20 The invention is not restricted to the details of construction shown and described, as it is evident that they are susceptible of modification.

I claim the following as my invention:

25 1. A sewing machine having a work table, a presser foot movable toward and from said work table, means for pressing the presser foot toward said table, a clamping bar slidably mounted on said presser foot and adapted to grip it and hold it against
30 movement away from said work table, a spring supporting said clamping bar in position to slide loosely on said presser foot, positive means for moving one end of said
35 clamping bar to cause it to grip and hold the presser foot against movement away from said table, and means operating periodically in the stitch forming operation to release said gripping means.

40 2. A sewing machine having a work table, a presser foot movable toward and from said work table, means for pressing the presser foot toward said table, a clamping bar slidably mounted on said presser foot and adapted to grip it and hold it against
45 movement away from said work table, hand operated means for withdrawing said presser foot from said table, a spring supporting said clamping bar in position to slide loosely on said presser foot, positive
50 means for moving one end of said clamping bar to cause it to grip and hold the presser foot against movement away from said table, and means operating at the end of
55 the stitch forming operation to release said gripping means.

3. In combination with a presser foot for a sewing machine having a work table and means for feeding the work, a sliding bar
60 upon which said presser foot is fastened, and means for operating said presser foot to clamp the work comprising a clamping lever slidably mounted on said bar, a movable support near one end of said lever for keep-
65 ing it out of clamping position, and posi-

tively operating means for moving the other end of said lever to clamp the bar and hold it down on the work.

4. In combination with a presser foot for a sewing machine having a work table and means for feeding the work, a sliding bar upon which said presser foot is fastened, and means for operating said presser foot to clamp the work comprising a clamping lever slidably mounted on said bar, a movable support near one end of said lever for keeping it out of clamping position, and positively operating means for moving the other end of said lever to clamp the bar, further movement of said positively operating means moving said lever, bar and support simultaneously.

5. A sewing machine comprising a work table, a presser foot coöperating therewith to hold the work, said presser foot being mounted on a reciprocatory holder having a slide, a clamp lever mounted on said slide, means for positioning said clamp lever loosely on said slide, said positioning means permitting bodily movement of said clamp lever, and means for tilting said clamp lever to cause it to grip said slide and hold said holder and presser foot fast against the work.

6. A sewing machine comprising a work table, a presser foot coöperating therewith to hold the work, said presser foot being mounted on a reciprocatory holder having a slide, a spring for pressing said member and presser foot against the work, a clamp lever mounted on said slide, means for positioning said clamp lever loosely on said slide to permit said holder to move relatively thereto, and means for causing said clamp lever to grip said slide and hold said holder and presser foot fast in adjusted position.

7. A sewing machine comprising a work table, a presser foot coöperating therewith to hold the work, said presser foot being mounted on a reciprocatory holder having a slide, a spring for pressing said member and presser foot against the work, a clamp lever mounted on said slide, means for positioning said clamp lever loosely on said slide to permit said holder to move relatively thereto, means for causing said clamp lever to grip said slide and hold said holder and presser foot fast in adjusted position, and means for reversing the operation of said gripping means to move said clamp bar holder and presser foot away from the work.

8. In combination in a sewing machine, a presser foot, a bar carrying said presser foot and mounted for reciprocatory movement, a clamp lever having a transverse opening the walls of which loosely embrace said bar, means for tilting said clamp lever to clamp said bar, and means for supporting

said clamp lever normal to said bar to permit it to slide through said opening, said supporting means comprising a pair of springs arranged to bear on both sides of 5 said clamp lever.

9. In combination in a sewing machine, a presser foot, a bar carrying said presser foot and mounted for reciprocatory movement, a clamp lever having a transverse 10 opening the walls of which loosely embrace said bar, means for tilting said clamp lever to clamp said bar, and means for supporting said clamp lever normal to said bar to permit it to slide through said opening, said 15 supporting means comprising a rod arranged parallel to said bar and having a pair of springs arranged upon it to bear on both sides of said clamp lever.

10. In combination in a sewing machine, 20 a presser foot, a bar carrying said presser foot and mounted for reciprocatory movement, a clamp lever having a transverse opening the walls of which loosely embrace said bar, means for tilting said clamp lever 25 to clamp said bar, and means for support-

ing said clamp lever normal to said bar to permit it to slide through said opening, said supporting means comprising a rod arranged parallel to said bar and having a spring arranged to bear on one side of said 30 clamp lever, said rod going through the clamp lever and having a collar on the other side of said clamp lever.

11. In combination in a sewing machine, a presser foot, a bar carrying said presser 35 foot and mounted for reciprocatory movement, a clamp lever having a transverse opening the walls of which loosely embrace said bar, means for tilting said clamp lever to clamp said bar, and means for supporting said clamp lever normal to said bar to permit it to slide through said opening, said supporting means comprising a rod arranged for lengthwise adjustment parallel to said bar and having a spring arranged to 40 bear on one side of said clamp lever.

Signed at St. Louis, Missouri, this 21st day of November, 1916.

HENRY P. SCHOENKY.
